UNITED STATES PATENT OFFICE

2,672,095

HIGH-PRESSURE HYDRAULIC PUMP

René Lucien and Eugen Ludwig Müller, Paris,
France, assignors to Societe d'Inventions Aero-
nautiques et Mecaniques S. I. A. M., Geneva,
Switzerland, a corporation of Switzerland

Application December 20, 1949, Serial No. 134,056

Claims priority, application France August 6, 1949

3 Claims. (Cl. 103—4)

1

Our invention relates to hydraulic pumps of the so-called "drum" or "barrel" type, i. e. in which pistons arranged about a common axis are adapted to be actuated, in their respective cylinders, by a wobble or swash plate which is inclined with respect to said axis and is actuated by a rotor.

Such pumps, which are in general intended for supplying a high-pressure liquid for actuating various apparatus, are frequently used in aircraft because of their regular output and their light weight and small bulk.

Our invention provides an improved pump of the foregoing type, which has a number of constructional arrangements whereby its weight and its bulk are fundamentally smaller than those of the known pumps of the same type.

A first feature of the invention consists in substituting for the usual arrangement, i. e. the axially staged arrangement, of said swash plate, its driving rotor and the race of said rotor, an interfitting arrangement of these members in such a manner that said plate is located substantially in the same transverse plane as the race, instead of being axially staggered with respect thereto, thereby enabling simultaneously a considerable shortening of the pump to be effected and all the stresses set up by the pistons to be transmitted to the pump body by said race.

A second feature of the invention consists in effecting the return of the pistons during their suction stroke by means of a second swash plate, the pistons thus operating between two swash plates. This method of drive makes it possible to substitute for the usual separate springs for retracting the pistons, a common spring which is housed coaxially in the barrel and to decrease still further not only the length but also the diameter of the pump.

A third feature of the invention, which is applicable to pumps provided with hollow pistons and inlet valves mounted on the pistons themselves, consists in fixing the opening abutment of each of the valves by means of resilient arms completely housed inside grooves which are cut in the bearing surfaces of the pistons so that said arms do not project above the sliding surface of the piston. This method of fixing the abutments enables the length of the pistons, and consequently that of the pump, to be decreased without decreasing the length of the useful bearing surface of the pistons.

A fourth feature of the invention consists in mounting, inside the rotor itself, a small auxiliary centrifugal pump of very small size, which

sucks, and forces into the casing of the main pump, the liquid which has accumulated between the fluid-tight joints of the main pump, where the shaft of the rotor passes into the casing. This arrangement is such that during the period of operation the outlet of the auxiliary pump is kept open by the centrifugal force itself, against the action of a spring which, when the pump is stopped, closes said outlet.

10 The accompanying drawing illustrates, by way of a non-limitative example, one embodiment of high-pressure barrel type pump exhibiting the features of the invention.

In the drawing:

15 Fig. 1 is a view in vertical section along the axis of the pump;

Fig. 2 is a view in transverse section of a piston along the plane projected on II—II in Fig. 1;
Fig. 3 shows the opening abutment of an inlet

20 valve, with its resilient arms.
1 denotes the pump body; 2 and 3 respectively denote the inlet and the outlet for the liquid; 4 is the cover which closes the pump body on the driving side.

25 A nut 5 secures the barrel 6 inside the body of the pump. In the barrel 6 are bored a number of cylinders, within which are respectively adapted to move axially perforated pistons 7 which rest by means of half-balls 8 on a swash 30 plate which in this case is constructed in the shape of a ring 9 mounted on balls 10 obliquely with respect to the axis X—X of the pump body, said plate receiving its oscillatory movement from a rotor 11 which is driven by the splined 35 driving shaft 11a and rotates on balls 12 inside a race 13 against which the cover 4 is adapted to bear.

It can be seen that, according to one of the characteristic arrangements of the invention, 40 the ring 9 is located inside the rotor 11 which is in turn located inside the race 13, so that the ring 9 is located substantially in the same transverse plane as the race 13, said plane, Z—Z, being approximately defined by the centre of the balls 12 and the centre of the ring 9.

This interfitting arrangement provides a very substantial reduction in the size of the pump in the axial direction, as compared with the known constructions in which the corresponding members are superposed on one another along the axis.

45 The return of the pistons 7 is effected by the action of a swash plate 14 provided with peripheral openings 15 by means of which it en-

gages said pistons, this retracting plate being adapted to bear by means of a common flat surface against the shoulders 16 respectively secured to said pistons. This bearing is ensured by a powerful spring 17, the action of which is exerted either directly, or by means of the member 18 and the ball 19, on the swash plate 14 in such a manner that said plate 14 describes approximately circular movements on the shoulders 16 with practically negligible friction.

It will be observed that this arrangement of the spring 17, which is housed coaxially in the barrel and is common to all the pistons, enables the transverse dimension of the pump to be reduced and that the provision of this collective spring, as compared with the separate springs usually used, enables the axial dimension of the pump to be reduced.

During the down-stroke of each piston 7, the corresponding inlet valve 20 is forced upwards by the liquid sucked into the cylinder, until it encounters its abutment 21. According to the invention, said abutment is provided with resilient arms 22 which are terminated by hooks 23. The arms 22 are respectively housed in longitudinal grooves 24 which are provided in the pistons 7 and inside which said arms are pressed with a high pressure, while the hooks 23 penetrate into transverse slots 25 likewise provided in the pistons 7. This arrangement of the resilient arms with hooks, which are completely housed in the actual body of the pistons and act as means for anchoring the abutment, enables the length of the pistons and consequently that of the pump to be reduced substantially.

The delivery of the liquid is effected, according to a method known per se, by the action of spring-actuated valves 26 through ducts 27 provided in the barrel 6.

The fluid-tightness of the pump at the point where the rotor 11 passes through the cover 4 is obtained by means of rotary joints 28—29—30.

The liquid which infiltrates between the joints 28 and 29 is subjected to the action of centrifugal force which projects it towards the opening of the pump through the duct 31 and the valve 32 which is in turn slightly opened by the action of centrifugal force. When the pump is inoperative, the spring 33 which bears against the pin 34 presses the valve 32 against its seat.

We claim:

1. A hydraulic pump of the barrel type comprising in combination: a pump body and a fixed, cylindrical member inside the pump body defining therewith two chambers separated by the cylindrical member and having respectively an inlet or suction port and an outlet or discharge port; a plurality of cylindrical bores in the cylindrical member defining working cylinders each

having a piston slideable therein, the bores being distributed equidistantly about, and having their axes parallel to, the axis of the cylindrical member; a dished drive rotor having a drive shaft 5 extending therefrom out of the pump body in alignment with said axis; means defining a race inside the dished rotor in a plane inclined to said axis; a first swash plate positioned to ride on the race and engage the pistons endwise to urge them into their respective cylinders; the pistons having shoulders adjacent the ends thereof engaged by the first swash plate and facing away from said ends; a second swash plate having apertures adjacent the periphery thereof embracing the pistons; a helical spring positioned in a central recess inside the cylindrical member and bearing on the second swash plate to cause engagement thereof with the piston shoulders, the individual coils of the spring being spaced from each other to permit a total contraction of the spring substantially equal to the stroke of the pistons; the pistons being hollow and communicating at their ends with the two chambers, and a non-return valve mounted on each piston 15 at the end thereof in communication with the chamber having a discharge port.

2. In a pump as claimed in claim 1 abutments limiting the opening of said valves, resilient arms connecting said abutments to their respective pistons, hooks at the free ends of said resilient arms and grooves provided in the sliding surface of said pistons and serving to house said resilient arms.

3. In a pump as claimed in claim 1, an auxiliary centrifugal pump for the recovery of leakages from the rotary joints of the rotor drive shaft through the body of the main pump, said auxiliary pump comprising a duct communicating, on the one hand, with said joints, and, on the other hand, with the inside of the pump body, a valve housed in said duct and subjected to the centrifugal force, and a spring for said valve biasing said valve in opposition to centrifugal force.
